BUTTER MOLD

Ralph B. Ausman, Meridian, Idaho, assignor of
one-half to R. C. Chattin, Boise, Idaho

Application October 11, 1937, Serial No. 168,320

5 Claims. (Cl. 31—45)

This invention relates to butter molds such as are used in creameries. The object of the invention is to provide new and useful improvements in a butter mold to be used in a creamery whereby the butter may be quickly and easily released and removed from the mold in a perfect shape, and in a sanitary condition.

An object of the invention is to provide a butter mold, made of any suitable metal, and which is strong and rigid either when open or closed, or when empty or full of butter. This is accomplished by having the mold open at two opposite corners to release the butter, said corners being provided with locks to hold them rigid when the mold is closed to receive the butter.

An object is to provide a mold which is simple to operate, and all in one piece which eliminates any parts that may be lost or misplaced, or damaged by dropping.

20 A further object is to provide a mold which is perfectly smooth on the inside, and which will not damage the butter wrapper when the butter is being removed from the mold.

25 A further object of the invention is to provide a mold which produces a cake of butter with parallel sides which may be cut into the conventional size pound packages with no waste, and also be easily released from the mold.

30 A feature of the mold is that it can easily be kept in a perfectly sanitary condition due to having all its parts open and exposed to any cleaning or sterilizing agent.

35 Another feature of the invention is that it is simple having very few parts, and it can be easily and cheaply manufactured.

40 These objects of the invention are hereinafter more fully described and claimed, and the preferred form of construction and association of the parts involving my invention is shown in the drawings in which—

Fig. 1 is a plan view with the corners open.

Fig. 2 is an elevation showing the mold opened.

45 Fig. 3 is a fragmentary plan view and with a cross section taken on the line A—A of Fig. 1.

Fig. 4 is a fragmentary top view of an open corner.

Fig. 5 is a fragmentary view of the underside of the top flange at an open corner.

50 Fig. 6 is a fragmentary elevation of either of the open corners.

Fig. 7 is an elevation view of the lever.

Fig. 8 is a vertical view of the lever.

55 Fig. 9 is an elevation view of the lever and connecting link.

Fig. 10 is a fragmentary cross section of an open corner and the operating lever and link.

Fig. 11 is a perspective view of the mold.

Fig. 12 is a plan view of the sheet of material from which two sides and the triangular flange 5 is formed.

Fig. 13 is a fragmentary perspective view of the under side of the top flange at an open corner.

Fig. 14 is a perspective view of the inside of 10 two sides and a fragmentary view of the bottom.

Referring to the drawings, in which for the sake of illustration is shown the preferred embodiment of the invention, the numeral 12 designates the bottom of the mold preferably in the 15 form of a square to which at its edges the sides 13 and 14, 15 and 16 are secured by common means such as welding. The sides 15 and 16 and the triangular flange 21 are all formed from a flat sheet of metal, see Fig. 12, also the flanges 17 are formed from the same sheet of metal. A cut is made at the point C' approximately to a depth of twice the width of the flange 17 and a cut is made also at F. The sheet is then folded 20 along the dotted line D, and then broken to a right angle along the dotted line E, forming flange 17. The sheet is again broken to a right angle along the line 18—18, with the flanges 17 outermost. The sheet is again broken along the dotted line G to a little greater angle than a 25 right angle thus forming the triangular flange 21. It will also be observed that the notch 23, see Figs. 12 and 13, is cut in the sheet before the sheet is first folded. The opposite sides 13 and 14 and the flanges 17 and 21' are formed in 30 identically the same manner.

At the corners 18' small square plates 18'' are welded to the ends of the flanges 17 thereby forming a rigid corner. The bottom plate 12 is welded at its edges to the bottom edges of the 40 sides 13, 14, 15, and 16 as at W, in Figs. 11 and 14, thus forming a rectangular box with vertical sides.

At the end 22 of the flange 17 an angular notch 23 better shown in Figs. 4, 5 and 13, is cut in 45 the lower fold of the metal forming the flange 17. Referring to Figs. 4, 6 and 13 it will be readily observed that the top edge of the triangular flange 21 when in position slides under the flange 17 at its end 22, and also between 50 the side wall and the notched edge 23 of the flange 17, this notched edge of the flange has a two purpose: first, it forms a retaining guide for the top of the flange section 21 which holds the sides 13 and 15 tight and in place when the 55

mold is closed; second, it will be observed that the flange 21 is broken to an obtuse angle from the side 16, see Fig. 4 and that the notch 23 is cut in the flange 17 so that the wide part of the 5 notch is furthermore from the end 22. Thus it will be observed that as the mold is opened, the flanges 21 when working against the angular notches 23 will move the sides 13 and 15 slightly outward and helps to loosen the sides of the 10 mold from the butter.

The numeral 24 designates a lever which is provided with the handle 25 at one end and with the hole 26 in the other end also with the hole 27 positioned close to the hole 26, and it will 15 be noted that the center of the hole 27 is above a line drawn through the center of the hole 26 and the center of the handle 25. The lever is also provided with the stop 28 which is in the form of a small ear turned at a right angle to the 20 lever body.

The numeral 29 designates a connecting link which is provided with the holes 30 and 31 in opposite ends, said link having an offset 32 in the form of a semicircle and approximately in 25 its center. By inserting a rivet 27' through the hole 27 in the lever 24 and through the hole 30 on the connecting link 29 and upsetting the ends of the same, Fig. 10, a hinge joint is formed between the lever 24 and the link 29. 30 By inserting the rivet 26' through the hole 30' in the side 13 and through the hole 26 of the lever 24 and upsetting the ends of the same a pivotal connection is formed and upon which the lever 24 pivots. By inserting a rivet 31' 35 through the hole 31' in the flange 21 and through the hole 31 in the connecting link 29 and upsetting the ends of the rivet, a bearing connection is made between the flange 21 and the link 29, thus forming an operable 40 mechanism to open and close the movable corner. A like lever and connecting link are secured in like manner to the side 15 and the flange 21' at the opposite corner of the mold. Referring to Fig. 2, the mold is shown with a 45 corner open, and it will be observed that the handle 25 of the lever 24 is up in the curved portion 32 of the link 29 and that the lever 24 pivots on the rivet 26' through the hole 26, and also that when the lever 24 is in the position 50 above described, that the rivet 27' which passes through the holes 27 and 30 in the lever and the link respectively is above the rivet 26' in the end of the lever 24 which causes the lever to be locked in position to hold the corner of the 55 mold open. The action is identical on the opposite corner of the mold.

By depressing the handle 25 of the lever and swinging it down and around the pivot rivet co-acting with the hole 26 of the lever, the lever 60 is brought up in approximately a horizontal position and is stopped by the ear 28 contacting the top of the link 29. During this operation the corner formed by the side 16 and the flange 21 is moved toward the edge 19 of the side 13, better shown in Fig. 10, until the two sides are together and form a tight corner when such sides are locked by the lever 24 and the link 29. This action is also identical on the opposite corner.

The bottom piece 12 is provided with the hole 33, the purpose of which is to admit air to enter the bottom of the mold as the butter is released. It will be observed that when the corners of the mold are opened there will be a bending action set up in the bottom of the mold which is along 70

the dotted line B-B, which action helps very materially in releasing the butter from the bottom of the mold. To the sides 13 and 15 are attached by common means the handles 34 and 35 which are used in handling the mold, said 5 handles fold against the sides when not in use. It is clearly shown in Fig. 2, that the edge 36 of the flange 21 can never be moved out past the edge 19 of the side 13 by means of the operating lever 24 and the connecting link 29, and 10 the same is true of the opposite corner. This insures a positive closing of the corner when the lever 24 is operated to close the corner, due to the fact that the edge 36 of the flange 21 can never come in contact with the edge 19 of the 15 side 13, and the same is true of the opposite corner.

From the above description it will be readily observed that the device will mold a product with horizontal sides and release the same without 20 marring the corners or sides, that it is strong and rigid and can be easily kept in a perfectly sanitary condition.

Having thus fully described my invention, its 25 utility and mode of operation, what I claim and desire to secure by Letters Patent of the United States is—

1. A butter mold having a bottom with four sides attached thereto thereby forming a rectangular parallelogram, the top of each side terminating in an outward flange, two opposite corners of the mold being rigid and two opposite corners being non-rigid, each of the non-rigid corners having a triangular shaped flange inclined at an angle to one of the sides and being 35 a continuation of said side, the base of said triangular flange being uppermost, angular notches cut on the underside of the first named flanges at their end at the non-rigid corners, the top of said triangular flanges being held between the sides of the mold and the notches cut in the flanges, means for movably connecting the triangular flanges to the adjacent sides of the mold, and a hole in the bottom of the mold. 40

2. A mold of the character described having a bottom and four sides attached thereto, the top of each side having a flange at an angle to and on the outside of the mold, with two corners rigid and two corners movable, one side at each of the movable corners having a flange at an angle thereto, means for movably connecting the said flanges to the adjacent sides of the mold, and means for holding the top of the second said flange in operable position with the first said flange. 45

3. A butter mold of the character described having a bottom and four sides attached thereto, with two opposite corners rigid and two opposite corners movable, one side at each of the movable corners having a flange at an angle thereto, 60 means for movably connecting the flanges to the adjacent sides of the mold, an operating lever attached to each of said adjacent sides of the mold, and means for connecting said operating levers to said flanges, said movable corners being 65 locked in either open or closed position by means of an operating lever.

4. A butter mold of the character described having a bottom and four sides attached thereto, the top of each side having a flange at an angle to and on the outside of the mold, with two corners rigid and two corners movable, one side at each of the movable corners having a flange at an angle thereto, means for movably connecting the said flanges to the adjacent sides of the mold, 70

means for holding the top of the second said flange in operable position with the first said flange, and means for locking the movable corners in open or closed position.

5. A butter mold of the character described having a bottom and four sides attached thereto, with two diagonal corners rigid and two diagonal corners moveable, an operating lever at-

tached to one side of the mold close to each of the movable corners, and means for connecting the operating levers to the adjacent sides of the mold at the movable corners, said movable corners being locked in either open or closed 5 position by means of an operating lever.

RALPH B. AUSMAN.
